(57) **CLAIM**

The ornamental design for a cover for air treatment system housing, as shown and described.

DESCRIPTION

FIG. 1 is a perspective top view of a cover according to the present invention.

FIG. 2 is a top view of the cover of the FIG. 1.

FIG. 3 is a bottom perspective of the cover of FIG. 1.

FIG. 4 is a bottom view of the cover of FIG. 1.

FIG. 5 is a side view of the cover of FIG. 1 (and the opposite side is a mirror image of this side); and,

FIG. 6 is an end view of the cover of FIG. 1 (and the opposite end is like the end shown in FIG. 6).
